COMBINATION ICE CREAM CARTON
AND TOYClarence S. Shank, Saginaw, Mich., assignor of
one-half to Robert Critchfield

Application June 10, 1950, Serial No. 167,364

5 Claims. (Cl. 46—11)

1

This invention relates to improvements in waxed paper cartons for ice cream and similar food products and pertains more specifically to certain printed indicia thereon which is designed to enable the user to construct three-dimensional toys or play things therefrom.

The size, shape, and construction of ice cream cartons have in recent years become more or less standardized due to the general acceptance in the trade of the machines for folding, filling, and sealing the containers; hence the designs or patterns contemplated by the present invention must necessarily be subjugated to cartons of uniform configuration and certain prescribed proportions.

One of the objects of the invention is to provide markings and directions on a carton blank of the character described above which will accommodate the conversion thereof into a toy or play thing for children or a display piece for use as an advertising medium.

Another object of the invention is to provide art work on the carton blank simulating, for example, the side elevational views and roof of a cottage rendered with sufficient artistic appeal to arrest the attention of a child and create a desire for the toy made therefrom, the ultimate purpose of the art work residing in a plan to stimulate the sale of the particular brand of goods packed in the carton.

Another object of the invention is to provide a design that will afford maximum utilization of a carton.

Another object of the invention is to provide a carton blank that may be converted into a toy of greater dimensions than the carton originally formed therefrom.

The paper stock generally employed in the production of ice cream cartons is of superior quality and texture, is relatively heavy in weight, and, after printing, the wax treatment to which it is subjected will enable it to withstand washing without injury thereto. Thus when the invention is applied to the exemplary embodiment referred to above the toys produced therefrom will be durable, attractive of appearance, and free from rugged, broken edges in or about the folded portions thereof. It will be understood, however, that the invention is susceptible of use in other environs and with other materials and that the ice cream carton and building structure illustrated herein are merely illustrative of one adaptation of the improvements encompassed by the inventive concept.

Further objects of the invention contemplate the provision of designs for the production of

2

three-dimensional toys from cartons which are customarily discarded after the initial use thereof, designs which may be printed on the carton blanks with little if any additional unitary cost, toys which are novel and attractive in appearance, and designs for toys that hold the interest and tax the dexterity of a child during the production thereof.

Other objects and advantages, more or less ancillary to the foregoing, and the manner in which all the various objects are realized will appear in the following description, which, considered in connection with the accompanying drawings, sets forth the preferred embodiment of the invention.

Referring to the drawings:

Fig. 1 is a plan view of a carton blank embodying the design and instruction data embraced by the present invention;

Fig. 2 is a view in perspective of a carton made from a plain blank of the form illustrated in Fig. 1;

Figs. 3, 4, and 5 are plan views of the several parts of the toy after such parts have been severed from the blank illustrated in Fig. 1 and fabricated in accordance with the instructions printed on the waste portions of the blank or concealed parts of the toy;

Fig. 6 is a composite view in perspective of the several parts of the blank after the initial folding operation thereof;

Fig. 7 is an end elevational view of the carton blank illustrating the initial step of assembly;

Fig. 8 is a view in perspective of a fragmentary portion of the toy illustrating the next step of assembly, the portions of the end tongues of the blank being broken away and shown in section in the interest of clarity; and

Fig. 9 is a view in perspective of the complete assembly.

Referring first to Fig. 1, the ice cream carton blank, which is configured to meet the structural and functional requirements of the packaging machines now in current use, comprises a panel 10 having vertical scores 11 (indicated by dot-dash lines) thereon defining the top 12, bottom 13, and sides 14 and 15 of the carton and a horizontal scored line 16 defining a tongue. A number of cuts 16a are made perpendicular to the vertical scores 11, thereby defining tongues 17, 18, 19 and 20 that form the end walls thereof. The face of the blank is printed with a design representing, in the exemplary case, the roof plan, chimney, and side elevational views of a cottage or dwelling of the form illustrated in Fig. 9.

During the printing operation slots *a*, *c*, *d*, and *f* are cut in the tongue *19* to form the keepers for certain locking tabs for the toy. The etching or other printing medium for the design also includes cutting and folding instructions, reference therein being made to the dash lines indicating the cuts to be made, the dotted lines indicating the folds, and the alphabetical characters of reference indicating the tabs and pierced openings in the fabricated parts of the toy.

It will be observed that the design is planned to fall within the confines of the blank and that the scored folding lines for the carton are preferably, though not necessarily, used in the construction of the toy. For example, the lines *16* in the blank form the bending guides for the roof, while the lines *11* facilitate the folds for the ends of the building structure.

The blank illustrated in Fig. 1, when folded and assembled with the tongues in interlocked relation, form the prismatical container shown in Fig. 2.

When the toy is constructed therefrom both ends of the carton are opened and the blank is then cut into along the dash line *21*. The upper panel (Figs. 1 and 3) is then cut along the dash lines *23*, *24*, and *25*, then the slots *26* and *27* are formed for the retention of the chimney, the slits *g* and *h* may be cut in the carton tongues *20*, and the material defining the slots *a*, *c*, *d*, and *f* is flexed to free the wax therein in order to accommodate the ready assembly of the similarly marked tabs in the lower tongue *17*. The lower panel (Figs. 1 and 4) is fabricated by cutting the stock along the dash lines *28*, *29*, *31*, and *32*, shearing the chimney from the marginal portion of the waste material in the tongue *18* as indicated by the dash lines *33* and *34*, cutting the slots *35* and *36* for the chimney, and cutting the dash lines *31*, *38*, *39*, and *40* to form the tabs *A*, *C*, *D*, and *F*. The two panels are next folded along the scored lines *11* and *16*, the dotted line *41* in the lower panel, and dotted lines *42* in the chimney to form the building elements indicated generally in Fig. 6.

In assembly the tab *A* is inserted into the slot *a* (Fig. 7), the tongue *B* into the slot *b*, the tab *C* into the slot *c*, the tab *D* into the slot *d*, the tongue *E* into the slot *e*, and the tab *F* into the slot *f*. During the assembly of the tabs and tongues as outlined above, the corner tabs *G* and *H* in the lower panel are inserted into the kerfs formed by the slits *g* and *h* in the upper panel as illustrated in Fig. 8. The folded chimney is then inserted into the slots *26*, *27*, *35*, and *36*, which operation completes the assembly of the toy shown in Fig. 9.

It will be recognized that reformation of the carton blank of Fig. 1 for the package of Fig. 2 is attained by the novel use of the original tongues, slots, and scored lines therein and through the provision of the additional interlocking parts planned in the design and indicated by the indicia printed on the blank. It will also be recognized that other pictorial studies and other designs similar in structure and function to the exemplary embodiment disclosed herein may be made without departing from the scope or spirit of the invention as claimed herein.

I claim:

1. A toy building constructed from a carton of parallelepiped form having two sides substantially larger than the other two sides, the toy building being formed from two portions of said carton, said carton being divided along a cutting

line at the juncture of one of the larger sides and one of the smaller sides, flaps extending from each end of the sides respectively, and slots formed in the flaps for joining the portions of the building into a composite structure wherein the large sides become the roof section of the building and the small sides become the side walls of the building, the physical dimensions of the building being larger than the carton from which the building is constructed.

2. A toy building constructed from a carton of parallelepiped form having two sides substantially larger than the other two sides, the toy building being formed from two portions of said carton, said carton being divided along a cutting line at the juncture of one of the larger sides and one of the smaller sides, flaps extending from each end of the sides respectively, slots formed in the flaps for joining the portions of the building into a composite structure wherein the large sides become the roof section of the building, the small sides become the side walls of the building, and the flaps form the ends of the building, the physical dimensions of the building being larger than the carton from which the building is constructed.

3. A toy building constructed from a carton of parallelepiped form having two sides substantially larger than the other two sides, the toy building being formed from two portions of said carton, said carton being divided along a cutting line at the juncture of one of the larger sides and one of the smaller sides, flaps extending from each end of the sides respectively, slots formed in some of the flaps and tongues on other flaps for engaging the slots thereby joining the portions of the building into a composite structure wherein the large sides become the roof section of the building and the small sides become the side walls of the building, the physical dimensions of the building being larger than the carton from which the building is constructed.

4. A toy building constructed from a carton of parallelepiped form having two sides substantially larger than the other two sides, said carton being divided along a cutting line at the juncture of one of the larger sides and one of the smaller sides, representations of portions of a building structure printed thereon, the roof structure being printed on the larger sides and the wall structure being printed on the smaller sides, flaps extending from each end of the sides respectively and wall structure representation being printed on said flaps, slots formed in some of the flaps and tongues formed on other flaps for engaging the slots, a chimney printed on one of said flaps for cutting out and placing on the roof, the side walls of the building being joined by said tongues and slots thereby forming a building without a floor, the physical dimensions of the building being larger than the carton from which the building is constructed.

5. A toy building constructed from a carton of parallelepiped form having two sides substantially larger than the other two sides, said carton being divided along a cutting line at the juncture of one of the larger sides and one of the smaller sides, representations of portions of a building structure printed thereon, the roof structure being printed on the larger sides and the wall structure being printed on the smaller sides, flaps extending from each end of the sides respectively and wall structure representation being printed on said flaps, slots formed in some of the flaps and tongues formed on other flaps for

engaging the slots, a chimney printed on one of said flaps for cutting out and placing on the roof, slots in the roof portion for receiving the chimney, the side walls of the building being joined by said tongues and slots thereby forming a building without a floor, the physical dimensions of which being larger than the carton from which the building is constructed.

CLARENCE S. SHANK.
